UNITED STATES PATENT OFFICE.

EDWARD BORNHOEFT, OF NEW YORK, N. Y., ASSIGNOR TO DAVID H. SCHMIDT, OF NEW YORK, N. Y.

PIANO-DAMPER.

SPECIFICATION forming part of Letters Patent No. 729,533, dated June 2, 1903.

Application filed March 18, 1903. Serial No. 148,294. (No model.)

To all whom it may concern:

Be it known that I, EDWARD BORNHOEFT, a citizen of the United States, residing at New York city, (Bronx,) county of New York, and State of New York, have invented certain new and useful Improvements in Piano-Dampers, of which the following is a specification.

This invention relates to a piano-damper which is so constructed that an accurate adjustment between the damper and the strings may be readily effected.

In the accompanying drawings, Figure 1 is a side view of my improved piano-damper; Fig. 2, an end view thereof. Figs. 3 and 4 are opposite side views of the damper-block; Fig. 5, a bottom view thereof; Fig. 6, a side view of the upper end of the damper-wire, and Fig. 7 a vertical cross-section through the center of the damper.

The letter *a* represents a slidable damper-block carrying a cushion *b* at each end above the strings *c*. At its center and between the cushions there is formed in the bottom of the block *a* a tubular mortise *a'*, communicating at its upper end with a tapped perforation *a*². The mortise *a'* opens at one side into an upright slot *a*³ and at its other side into a recess *a*⁴.

The damper-wire *d* is doubled at its upper end, the downwardly-extending arm *d'* carrying a tubular sleeve *e*. Into this sleeve is fitted a tight core *e'*, provided with a tapped axial perforation *e*² and with a second upright perforation into which the arm *d'* is fitted. The sleeve and core collectively constitute a tapped and perforated head. The thread of the axial perforation *e*² runs in a direction opposite to that of the perforation *a*², both perforations being engaged by a common right-and-left screw *f*, the head *f'* of which projects centrally upward from the damper-block *a*.

In assembling the parts the sleeve *e* is received by the mortise *a'*, the upper end of wire *d* is received by the slot *a*³, while the recess *a*⁴ serves to accommodate the wire of the adjoining damper-block. The screw *f* on being inserted will connect the head to the damper-block, and by turning the screw in either direction the damper-block will be moved upward or downward along the head, so that the elevation of the cushions *b* above the strings *c* may be readily adjusted.

It will be seen that by my invention the screw for effecting the adjustment is readily accessible, the damper-block is properly guided during its movement along the head, and an accurate adjustment may thus be easily effected.

What I claim is—

1. A piano-damper composed of a damper-wire, a tapped head secured thereto, a tapped mortised damper-block, and a screw that engages the block and head, substantially as specified.

2. A piano-damper composed of a damper-wire having a bent upper end, a tapped head secured thereto, a tapped mortised damper-block, and a right-and-left screw that engages the block and the head, substantially as specified.

3. In a piano-damper, a tapped damper-block having a mortise and a communicating slot, combined with a damper-wire having a bent upper end, a tapped head secured thereto, and a right-and-left screw that engages the block and the head, substantially as specified.

Signed by me at New York city, (Manhattan,) New York, this 17th day of March, 1903.

EDWARD BORNHOEFT.
